UNITED STATES PATENT OFFICE.

CHARLES K. FRANCIS AND DAVID G. MORGAN, OF TULSA, OKLAHOMA, ASSIGNEES OF ONE-HALF TO COSDEN & COMPANY, OF TULSA, OKLAHOMA, A CORPORATION OF OKLAHOMA.

ART OF REFINING PETROLEUM PRODUCTS.

1,313,629.

Specification of Letters Patent.

Patented Aug. 19, 1919.

No Drawing.

Application filed December 16, 1918. Serial No. 267,067.

To all whom it may concern:

Be it known that we, CHARLES K. FRANCIS and DAVID G. MORGAN, citizens of the United States of America, and residents of Tulsa, in the county of Tulsa, State of Oklahoma, have invented certain new and useful Improvements in the Art of Refining Petroleum Products, of which the following is a full, clear, and exact description.

- 10 This invention relates to improvements in the art of refining petroleum, or petroleum products, and more particularly to a process of obtaining water white petroleum products. The invention is especially adapted 15 for use in the treatment of cracked products such as the gasolines, naphthas and kerosenes obtained from the distillates of pressure stills, or cracking stills. Products of cracking stills known as pressure distillate, cracked gasoline, kerosene and the like have an objectionable odor and color which should be eliminated before the cracked products are sold to the consumer, for either the color or the odor would very materially 20 reduce the market value of the products. It has, however, been both difficult and expensive to obtain permanent water white products by the refining operations to which the cracked distillate is ordinarily subjected. 25 One of the most difficult problems lies in the permanent elimination of the color. Some of the earlier processes produce water white products which eventually turn to a yellowish or brownish color when left for a 30 while standing when exposed to the light, this being particularly true of the kerosene fraction obtained by redistilling cracked distillate.

One of the objects of the present invention is to eliminate or improve the objectionable odor of petroleum products, especially the gasolines, naphthas and kerosenes obtained from cracked distillate.

Another object is to permanently remove, 45 and absolutely eliminate from the products, the property of darkening in color when exposed to light.

In the preferred form of the invention, all of these objects are accomplished by 50 commingling saponaceous material with the petroleum, or petroleum product, to be treated, and distilling the resultant mixture. More specifically stated, the saponaceous material may be prepared by partially or completely saponifying a fat or suitable oil with

caustic soda (sodium hydroxid). When saponification is complete, sodium carbonate is added. This excess alkaline carbonate has very materially increased the efficiency of the saponaceous mixture. 60

In the treatment of cracked distillate resulting from the distillation of gas oil under pressure, we have found that the saponaceous mixture may consist of lard 2 parts, sodium hydroxid 0.3 part, and sodium carbonate 3 parts. About one pound of this mixture may be used for each barrel of the distillate to be treated. The distillate may be subjected to a preliminary treatment with acid and washing with alkali, but it is not 70 necessary to completely carry out the ordinary "sweetening" operation at this stage.

The saponaceous material, containing an excess of the alkaline carbonate is placed in a still where it commingles with the hydrocarbon liquid to be treated, and the distillation is carried out in any suitable manner, with fire alone, or with fire and steam, or with steam alone. The still conditions may be varied according to the product desired; 75 for example, if a light distillate is being treated to obtain gasoline or naphtha, steam alone may be used to heat the mixture, or if a low gravity liquid such as gas oil is to be distilled under pressure, fire alone may be 80 used to heat the charge. It will therefore be understood that the new process can be carried out while the hydrocarbon liquid is undergoing one of the ordinary distilling operations to which it is subjected in the re- 85 refinery. The distillation is an important step in the process herein disclosed, but it adds almost nothing to the cost of removing the 90 color, odor, etc.

We have found, however, that the charge 95 contained in the still should be agitated so as to prevent the ingredients of the special mixture from settling to the bottom of the still, at the same time causing them to thoroughly commingle with the hydrocarbon liquid. This may be accomplished by forcibly circulating the charge in the still, or by the natural ebullition of the boiling liquid, or by mechanical agitators mounted in the still. 100

Actual experience has shown that this 105 simple process, involving a distillation of hydrocarbon liquid commingled with a saponaceous mixture, results in a water white distillate, and in the permanent re- 110

moval of the property of the darkening in color when left standing or when exposed to light. It also very greatly improves the odor of the products. In carrying out the new process we have also found that the charge can be reduced lower than is customary. This results in an increased yield of marketable kerosene, which is of course more valuable than the residual product in the still.

Although we have herein disclosed the specific details of a preferred method, pointing out animal fat as the preferred saponifiable material, and also setting forth the precise proportions of several ingredients which have given entire satisfaction, it is to be understood that the invention comprehends modifications within the scope of the claims hereunto appended. We may add, however, that the liquid undergoing treatment must be distilled while commingled with a saponaceous material together with an excess of sodium carbonate. The mixture should be agitated during the distilling operation and it is essential to use an excess of alkaline carbonate in this saponaceous mixture.

By "alkali" is meant alkaline carbonates as well as the caustic alkalis.

30 We claim:

1. In the art of refining petroleum hydrocarbons to obtain water white products, the process which comprises commingling with the hydrocarbon liquid a saponaceous mixture containing an excess of alkali, and distilling the resultant mixture.

2. In the art of refining petroleum hydrocarbons to obtain water white products, the process which comprises commingling a

saponifiable substance with an alkali to produce a saponaceous mixture, commingling said saponaceous mixture with a hydrocarbon liquid, and agitating and at the same time distilling the resultant mixture.

3. In the art of refining cracked petroleum distillates, the process of obtaining water white products which comprises commingling with the distillate to be treated a saponaceous mixture, formed by combining an animal fat and an excess of alkali, and distilling the resultant mixture.

4. The herein described process of treating cracked petroleum distillates to obtain water white products, which comprises saponifying a fat, adding an excess of alkali, commingling this saponaceous mixture with the cracked distillate to be treated, distilling the resultant mass, and agitating the mass while it is undergoing distillation.

5. The herein described process of treating cracked petroleum distillates to obtain water white products, which comprises saponifying animal fat with caustic soda, using 2 parts of fat, 0.3 part of caustic soda and adding 3 parts of sodium carbonate, and when saponification is complete adding an excess of alkali, commingling this saponaceous mixture with the cracked distillate to be treated, using about one pound of the saponaceous material to each barrel of the cracked distillate, distilling the resultant mixture, and agitating the mixture while it is undergoing distillation.

In testimony that we claim the foregoing we hereunto affix our signatures.

CHAS. K. FRANCIS.
DAVID G. MORGAN.
